UNITED STATES PATENT OFFICE.

MURRAY C. BOYER, OF RIVERTON, NEW JERSEY, ASSIGNOR TO PHILADELPHIA STEEL & WIRE CO., OF PHILADELPHIA, PENNSYLVANIA, A CORPORATION OF NEW JERSEY.

REINFORCING MEANS FOR CONCRETE CONSTRUCTION.

1,147,603.

Specification of Letters Patent.

Patented July 20, 1915.

Application filed November 7, 1910. Serial No. 591,122.

To all whom it may concern:

Be it known that I, MURRAY C. BOYER, a citizen of the United States, and a resident of Riverton, Burlington county, New Jersey, 5 have invented certain Improvements in Reinforcing Means for Concrete Construction, of which the following is a specification.

My invention relates to reinforcing means for concrete construction, and it consists of 10 certain improvements in deformed bars or rods more fully described hereinafter and shown in the accompanying drawings, in which:

Figure 1, is an elevation of a deformed 15 bar embodying my invention; Fig. 2, is a cross-sectional view of the same; Fig. 3, is a perspective view of the bar shown in Fig. 1, and Figs. 4 to 12, both inclusive, illustrate other deformed bars within the scope of my 20 invention.

The purpose of metallic reinforcing means is thought to be so well known as to require no extended discussion, and the object of using a deformed bar is to increase the resistance to separation of the reinforcing bar and the concrete under the strains of tension. 25

My invention comprehends the use of bars of substantially the same area throughout their length with individual isolated projections or fins to offer the desired resistance to longitudinal movement in the mass of concrete. These projections may be disposed at staggered intervals throughout the length 30 of the bars. In the polygonal or rectangular bars, the projections are disposed at diagonally opposite corner edges, extending part way across the plain faces of the bars adjacent such corner edges, and the latter are preferably rounded. In other words 35 my improved bar has individual isolated projections in staggered relation disposed at diagonally opposite sides of the bar and having their greatest cross sectional area upon the flat sides of said bar. This construction offers no difficulty in the rolling of the bar with the projections formed integral therewith.

In the preferred form, the projections describe an arc of a circle from one plane surface of the bar to another adjacent the corner edge, as illustrated in Figs. 1, 2 and 3, in which 1 represents the bar, and 2 the 50 projections.

In Figs. 4, 5 and 6, a projection 2^a with

a raised portion 3 substantially centrally disposed in that portion of the projection adjacent each of two plane surfaces of the bar is shown.

In Figs. 7, 8 and 9, the outer edges of the 55 projections 2^b parallel the plane surfaces of the bar, joining in a curved outline around corner edges of the same.

In the embodiment of my invention shown in Figs. 10, 11 and 12, I provide a bar 1^a having a rounded or curved cross section; 60 elliptical or oval, for instance; the projections 2^c being disposed on opposite sides of the broad surfaces of the same in staggered relation and extending from the curved portions of short radius only a part way over 70 said surfaces.

In all instances, the projections are preferably of rounded contour and blend with the plane or curved surfaces of the bars at their ends.

Since all of the bars are of substantially uniform cross section throughout their length and have the friction producing means in the form of projections providing an added amount of metal, there is no difficulty in the operation of bending the same to form truss members or danger of fracture during such bending. The disposal of the 75 projections in the manner indicated provides the necessary amount of frictional resistance 80 to longitudinal movement without an excess of metal.

I claim:

1. A straight bar for reinforced concrete construction having individual isolated projections in staggered relation disposed at diagonally opposite surface portions of the bar, said projections being arched and having their greatest cross sectional area centrally disposed with respect to said arched portion, and said projections lying in planes parallel to the transverse axis of the bar and being disposed substantially at regular intervals; with plain portions of the bar between the projections and plain portions extending longitudinally of the bar intermediate the rows of projections.

2. A bar for reinforced concrete construction having a plurality of faces and a plurality of corners, a series of individual isolated projections disposed on all the faces of said bar, said projections having their greatest cross sectional area upon such faces and

joining around two of the corners of the bar diagonally opposite each other, said several projections lying in planes parallel with the transverse axis of the bar at substantially regular intervals, with plain portions extending longitudinally of the bar intermediate the rows of projections.

In testimony whereof, I have signed my name to this specification, in the presence of two subscribing witnesses.

MURRAY C. BOYER.
